Des. 215,895
Patented Nov. 4, 1969

215,895

BOAT HULL

Lawrence P. Feer, Cazenovia, and Thomas L. Faul,
Skaneateles, N.Y., assignors to Woodall Industries
Inc., Detroit, Mich., a corporation of Delaware

Filed Feb. 3, 1969, Ser. No. 15,599

Term of patent 14 years

Int. Cl. D12—06

U.S. Cl. D71—1

FIGURE 1 is a perspective view of a boat hull showing our new design; and

FIGURES 2, 3, 4, and 5 are respectively plan, side elevational, front elevational, and rear elevational views thereof.

We claim:

The ornamental design for a boat hull, substantially as shown and described.
